UNITED STATES PATENT OFFICE.

CHARLES E. VAN HECKE, OF STEVENS POINT, WISCONSIN.

MANHOLE FRAME, COVER, AND HYDRANT-HOLDING ASSEMBLAGE.

Application filed December 23, 1926. Serial No. 156,723.

The invention relates to improvements in manhole frames and covers for use in connection with hydrants, and it is the object of such invention to provide a new and improved construction and arrangement of parts, producing a curved seat at one side of the manhole frame, and means for holding a hydrant engaged with the seat in such manner that the hydrant may be readily disconnected from the manhole frame and removed when it is necessary to make repairs or to replace it with another hydrant.

With the foregoing in view, the invention resides in the novel subject matter hereinabove described and claimed, the description being supplemented by the accompanying drawings.

Figs. 1 and 2 are perspective views showing the relation of the improved frame with a hydrant.

Fig. 3 is a perspective view illustrating the manner in which the hydrant is finally tightened in its holding means.

Fig. 4 is a vertical sectional view through the new assemblage of parts, illustrating a portion of the hydrant in elevation.

Fig. 5 is a perspective view of the manhole frame, the manhole cover, and the hydrant-holding strap shown in the preceding views.

Fig. 6 is a perspective view illustrating the manner in which a hydrant having an exceptionally large base may be secured to the frame.

Fig. 7 is a horizontal section on line 7—7 of Fig. 6.

Fig. 8 is a perspective view of the hydrant-holding strap and the anchoring hooks therefor, shown also in Figs. 6 and 7.

Fig. 9 is a fragmentary horizontal section on line 9—9 of Fig. 3.

Fig. 10 is a small side elevation showing a different form of frame.

In the drawings above briefly described, 45 10 designates a circular manhole frame, said frame having a substantially circular side wall 11, a base flange 12 projecting outwardly from the lower edge of said wall, and reinforcing ribs 13 extending between said wall 50 and flange. The general circular formation of the wall 11 is interrupted by an outwardly bowed portion 14 providing a substantially semi-cylindrical seat at the inner side of the wall, to engage one side of a hydrant 55 15. In the form of construction shown in Figs. 1 to 5, one manner of securing the hy-

drant in the seat 14, is shown. In these views, 16 designates a substantially semi-circular strap having laterally extended ends 17, said strap being disposed at the portion 60 of the hydrant opposite the seat 14 and having said ends 17 received in notches 18 formed in the upper edge of the seat-forming portion of the wall 11. The lower edge of the strap 16 is provided with an outwardly projecting flange 19 flush with an internal ledge 19' of the frame 10, said flange and ledge jointly supporting a cover 25 notched at 26 to engage the strap 16.

Between the notches 18, the upper edge 70 of the seat-forming portion of the wall 11 is preferably formed with a notch 20 non-rotatably receiving the head 21 of a horizontally disposed bolt 22. A nut 23 is threaded on this bolt and contacts with the inner side of the wall 11, so that by turning the nut in one direction, the bolt may be forced inwardly to force the hydrant toward the strap 16. If the hydrant be of a diameter smaller than that of the seat 14 and strap 80 16 combined, a filler or fillers will be positioned between the strap and hydrant before tightening the nut 23. A filler has been shown in the form of a curved rod 24' but other suitable fillers could be used, and if the hydrant be of larger size, the filler may be omitted and the parts 22—23 also.

After the hydrant is positioned between the seat 14 and strap 16, a pipe jointer or other desired means (not shown) may be 90 passed around it, and oakum and clay used also if necessary, to form a dam, permitting a molten sealing material to be poured around the hydrant, between the latter and the parts 14—16. When this sealing material sets, it forms a tight seal 24 between the hydrant and the aforesaid parts 14—16.

When the hydrant is to be removed for repairs or to be replaced with another hydrant, the strap 16 may be hammered upwardly so that its lateral ends 17 are freed from the notches 18. Then, the hydrant may be disconnected from the main and removed from engagement with the seat 14. The packing material 24 is of course also removed and when either the same hydrant is to be reset or another installed, the resetting or installing operation may be easily performed.

The strap 16, herein disclosed, is formed of a length of angle metal with end portions of its horizontal flange cup away, the ver-

tical flange being backed up by a metal bar 16^a. I am not restricted however to this construction and if desired, a one-piece cast or forged strap may be employed.

5 When a hydrant is to be held, having a base of maximum size, such as shown at 15' in Fig. 6, a strap 16' having lateral ends 17', is engaged with the portion of the hydrant opposite the seat 14 and at or near the lower 10 end of this seat. Then, bolts 27 having hooks 28 at one end, are engaged with the base flange 12 and pass through openings in the lateral ends 17'. When the nuts 29 of these bolts are tightened, the hydrant will 15 be effectively held in the seat 14.

A cover similar to that above described, will of course be used when the hydrant is held as shown in Figs. 6, 7 and 8, but the notch in the edge of the cover may then 20 directly engage the hydrant.

Frames other than that so far described may be used. For instance, the frame 10' of Fig. 10 is desirable in some cases having a flange 12' at its upper edge. 14' of 25 this view indicates a seat corresponding to the seat 14, and 13' are merely bracing webs.

Any form of the invention will permit quick and easy setting or removal of a hydrant, will securely hold the latter in place, 30 and will function also as a manhole frame and cover.

Excellent results have been obtained from the details disclosed, and they may therefore be followed if desired. However, within the 35 scope of the invention as claimed various changes may be made.

I claim:

1. An assemblage of the class described comprising a manhole frame having an upper 40 standing side wall, the latter being formed with an outwardly bowed portion providing a hydrant seat at the inner side of the frame, releasable means for holding a hydrant in said seat, and a manhole cover resting on 45 the frame and having a notch for disposition at the side portion of the hydrant opposite the aforesaid seat.

2. An assemblage of the class described comprising a manhole frame having an upper 50 standing side wall, the latter being formed with an outwardly bowed portion providing a hydrant seat at the inner side of the frame, a curved strap for disposition around the side of the hydrant opposite said seat,

and means for connecting the strap to the 55 frame.

3. An assemblage of the class described comprising a manhole frame having an upper standing side wall, the latter being formed with an outwardly bowed portion providing 60 a hydrant seat at the inner side of the frame, a curved strap for disposition around the portion of the hydrant opposite said seat, said strap having laterally extended ends, and means engaging said ends for holding 65 the strap in fixed relation with the aforesaid wall.

4. An assemblage of the class described comprising a manhole frame having an upper standing side wall, the latter being formed with an outwardly bowed portion providing 70 a hydrant seat at the inner side of the frame, and a curved strap for disposition around the portion of the hydrant opposite said seat, said strap and wall having releasably engaged means for supporting the strap in position to retain the hydrant engaged with the seat.

5. An assemblage of the class described comprising a manhole frame having an upper standing side wall, the latter being formed with an outwardly bowed portion providing a hydrant seat at the inner side of the frame, and a curved strap for disposition around the portion of the hydrant opposite said seat, said strap having laterally extended ends, the upper edge of the said wall being formed with notches removably receiving 85 said lateral strap ends.

6. A structure as specified in claim 2; the upper edge of the seat-forming portion of said wall having a notch, a bolt to engage the hydrant, said bolt having a head non-rotatably received in said notch, and a nut threaded on said bolt and contacting with 90 the inner side of said wall portion, tightening of the nut serving to project the bolt inwardly to tightly engage the hydrant.

7. A structure as specified in claim 2; said strap having an outwardly projecting 100 flange and said wall being provided with an internal ledge, the upper sides of the flange and ledge jointly forming cover supporting means.

In testimony whereof I have hereunto 105 affixed my signature.

CHARLES E. VAN HECKE.
